UNITED STATES PATENT OFFICE.

LAURA M. BRONSON, OF NEW YORK, N. Y.

FASTENING FOR STUDS OR BUTTONS.

Specification forming part of Letters Patent No. **39,461**, dated August 11, 1863; antedated December 31, 1862.

To all whom it may concern:

Be it known that I, LAURA M. BRONSON, of the city, county, and State of New York, have invented a new and useful improvement in fastenings for buttons on coats, vests, pants, and other garments, of which the following is a full, clear, and exact description, reference being had to the accompanying drawings, making part of this specification, in which—

Figure 1 is a top view of my improved fastener. Fig. 2 is a bottom view of same. Fig. 3 is a view showing button and fabric. Fig. 4 is an S-shaped wire with counter-eye on cross-bar.

The fastenings used for the purposes above-mentioned prior to my said invention consisted of a circular spiral ring, which, on being turned into the eye of the button, afforded no stay to the cloth, while any strain upon the button caused the whole ring to project toward the body or limb of the person, and the single point embraced by the button-eye to be drawn into the eyelet, so as to rend or greatly strain it. The wire loop sometimes used for the purpose was open to similar objections, while the more recent invention of the button with a screw of metal and gutta-percha nut cannot possibly give any stay to the cloth or effect a permanent fastening, since the continued friction in wearing will tend to unscrew the fixture, and the sharp edge of the screw-thread will soon wear the nut so as to make it inoperative.

Buttons attached by the ordinary method of sewing-cord cannot, of course, be readily removed and reattached without much inconvenience—to men especially who are occupied at sea or in camp.

By my invention the above-mentioned dif-

ficulties are avoided; and my invention consists in making such fastenings of a metal ring or S-shaped wire, with a portion so arranged as to form a cross-bar to the other portion, the part so formed being bent in the middle so as to form a counter eye or rest for the button-eye, so that it may remain fixed in place, and not work or slide upon the bar.

In attaching the buttons in place on any garment, an eyelet is made with a bodkin, or any pointed instrument, the eye of the button is forced through, and the ring or S-shaped wire turned into the eye until the eye of the button slips into the eye of the fastener. Now, when any strain is exerted upon the button, the entire size of the ring or S is drawn against the cloth, and thus affords a thorough and efficient stay thereto, so that any extra staying by cloth, or even working of the eyelet, is rendered unnecessary.

The advantage obtained by my said invention consists in the facility it affords for attachment, detachment, and reattachment of the buttons, together with the neat and compact form they can be made to assume when in place, and also the protection thus afforded to the fabric, securing and staying it against all the strain to which buttons are liable.

Having thus described my invention, what I claim, and desire to secure by Letters Patent, is—

The ring or S-shaped wire of metal with the cross-bar and counter-eye, as shown, and for the purposes set forth.

LAURA M. BRONSON.
